INJECTOR-TIMER FOR INTERNAL-COMBUSTION ENGINES

Eugene Silber, New York, N. Y.

Application July 15, 1942, Serial No. 451,032

11 Claims. (Cl. 103—38)

This invention relates generally to improvements in fuel-supply controls for internal combustion engines and, in a more particular sense, is concerned with a novel injector pump suitable for use on engines of the Diesel type.

It is an object of this invention to provide such a fuel supply which will be simple in its construction and operation and rugged in all its parts, but which will feed to the engine cylinders the exact amount of fuel desired, and which may be adjusted to meet external conditions with ease while the engine is running.

More specifically it is an object to provide a device of the above character having a common pump for all the engine cylinders but distributing the fuel to the separate cylinders in the order of firing by controlled distributing conduit, the whole having the maximum of simplicity.

As is generally known, in Diesel-type internal combustion engines, fuel oil is forcibly injected into each of the cylinders of the engine in sequence, the order of injection being determined by the type of crank shaft used and the timing of the successive injections, together with the quantity of fuel injected, being controlled both by the speed at which the engine is operating and the effective working volume of the cylinders. Inasmuch as cylinder-volumes and timing of engines made by different manufacturers vary over a wide range, say from less than about two hundred seventy cubic inches for small engines up to more than seventeen hundred cubic inches for larger type mobile engines, it has been customary to design and use, with each type of engine, an injector pump particularly suited to its requirements.

It follows from the foregoing that each of the types of injector pumps now in use is unique in the sense that it functions with but one type of Diesel engine requiring a peculiar timing of injections and specific volume of injected fuel. Obviously these pumps may not be used interchangeably upon other types of engines which would require different timing and different volumes of injected fuel. Existing types of injector pumps are mostly of the crank-shaft-driven piston type, hence the latitude within which the effective displacement of the pump must be made is controlled by the stroke of the shaft, which precludes sufficient adjustment to permit any degree of interchangeability. Also, for reasons that will be obvious to those versed in this field of invention, it is difficult, if not as a practical matter impossible, to vary the timing of injector

pumps of the types now most commonly in use, while the engine is in operation.

It is the chief object of the present invention to provide a novel and useful type of injector pump that can be used entirely satisfactorily upon Diesel engines having widely different requirements as regards volume of fuel injected and the timing of the injections.

Another object of the invention is to provide a pump of the type mentioned which can be easily and economically constructed without requiring use of highly specialized equipment and which, because it includes but a relatively small number of moving parts, is both less subject to wear and easier to repair than certain types of injector pumps now in use.

A further object of the present invention is to provide a fuel-control means for internal combustion engines which, in the event of breaking of the governor control bar, or of same being disconnected from pump for any reason—a type of accident that is not uncommon, will serve to diminish the speed of and eventually stop the engine, instead of increasing the fuel supply and causing the engine to speed excessively and destroy itself as occurs with types of pumps now in use.

A notable advantage of the injector pump according to this invention over existing types of injector pumps is that the pump plunger is given positive motion by means of a cam mounted upon and operated by the fluid distributor mechanism, thus permitting the entire apparatus to be constructed in a manner such as to occupy but small space, also the same plunger is used to vary or meter the amount of fuel that may be necessary to maintain the speed of the engine and to carry proper load.

An important feature of this novel injector-timer pump is that it permits not merely the adjustment of the time interval between injections as is necessary to allow interchangeability of the pump between different engines, but that it also permits collective advancement of the timing of the injections as the speed of the engine increases without otherwise interfering with the operation of the engine, thus making possible more efficient operation by minimizing fuel waste.

Other objects, advantages, and features of the novel injector-timer pump according to the present invention will be apparent to those versed in this field of invention during the course of the following description.

Regarded in certain of its broader aspects, the novel injector-timer pump according to this in-

vention comprises a cylindrical block having a plurality of fuel distributor valves therein, successively operable by a common rotating cam element; a variable displacement plunger-type force pump also in said block, connected to a fuel supply and to said distributor valves, periodically operated by means associated with said rotating cam element; means for altering the displacement of said pump; and a valve, controlling the connection of the pump to the fuel supply, for closing the connection periodically while the pump is discharging fuel through the distributor valve.

To facilitate a better understanding of the novel pump according to the present invention and of its mode of operation, a specific embodiment of the invention, illustrated in the accompanying drawings, will now be described, but it is clearly to be understood that this particular application of the principles of the invention is provided by way of illustration merely, not by way of limitation.

Referring to the drawings:

Figure 1 is essentially a side elevational view of a device embodying the principles of this invention;

Figure 2 is substantially a horizontal sectional view of the device shown in Figure 1, taken along the line 2-2 thereof;

Figure 3 is essentially an enlarged side elevational view, partly in vertical sectional view, of the device illustrated in Figure 1;

Figure 4 is substantially a vertical sectional view of the device shown in Figure 3, taken along the line 4-4 thereof;

Figure 5 is essentially a vertical sectional view of the device shown in Figure 3, taken along the line 5-5 thereof;

Figures 6 and 7 are enlarged detail views showing pump cams and valve operating hinges;

Figure 8 is substantially a vertical sectional view of the device illustrated in Figure 1, taken along the line 8-8 thereof;

Figure 9 is a detail view of a modified plunger head guide for the pump plunger forming a part of the device illustrated in Figure 3; and

Figure 10 is a modification of the discharge valve guide for the plunger pump forming part of the device also illustrated in Figure 3.

Referring now to the drawings which form a part of this specification, and particularly to Figure 1 thereof, it will be noticed that the novel injector-timer pump according to this invention comprises a base number 20 from which extend supporting standards 21 and 22 in the first of which is journaled the drive shaft 23 that operates the device, and in the second of which is mounted, preferably integrally formed therewith, a block, generally designated as 24, that encloses and contains the injector pump proper and the control valves associated therewith. Spacer bars 25, 26, and 27 fastened to the block 24 and the standard 21, serve to maintain the parts rigidly aligned in the desired spaced relationship.

The block 24, which is substantially cylindrical in shape, is provided with a chamber 28 opening through one face of the block but closed at its opposite end, see Figure 3, wherein a close-fitting plunger 29 is slidably mounted. It will be noted that the block is composed of two parts, 24a and 24b, which are bolted together essentially as shown and provided with a suitable gasket to assure proper sealing. The plunger is normally urged away from the closed end of the chamber 28 by a spring 30 that presses against

a portion of the block and a collar 31 on the plunger 29. A cap 32, seated in the block 24, engages with the collar 31 thus limiting the motion of the plunger 29 which can be imparted by the spring 30. A passage 33, formed in the block 24, communicates with the chamber 28 and with the inlet connection of the fuel supply line 34, substantially as shown. A sliding valve 35, slidably mounted in an opening 36 formed in the block 24, is arranged to control fuel flow through the passage 33, and is normally urged into opened position by a helical spring 37 which presses against a portion of the block 24 and an annulus 38 integrally formed upon the stem of the sliding valve 35 essentially as illustrated. A cap 39, seated in the block 24, and engaging with the annulus 38, serves to limit movement of the sliding valve 35 by the spring 37. A dog 40, slidably mounted in an opening 41 formed in the spacer bar 26, abuts against a projecting end portion of the sliding valve member 35, thus permitting movement and operation of the valve by motion of the dog as will be subsequently described.

A plurality of distributor valves 42, 43, 44, 45, 46, and 47, in this instance six in number but corresponding to the number of cylinders in the engine with which the pump is used, are close fittingly and freely slidably mounted in openings formed in the block 24. Each of the valves differs from each of the others only in its placement in the block, and each is connected to the fuel inlet orifice of a corresponding engine cylinder through the supply lines 48. In each of the connecting supply lines a spring-urged check valve is provided to assure unidirectional fluid flow to the engine cylinders. Referring to Figure 2 of the drawings, it will be noticed that the typical valves 43 and 46 are provided with check valves 49 and 50 respectively, and that the valves, such as 43 and 46, are normally urged into closed position by springs 51 that press against parts of the block 24 and annular projections upon the valve members. An annular channel 52, formed in the block 24, communicates with each of the valves 42, 43, 44, 45, 46 and 47, and with the passage 33 communicating with the pump chamber 28, in a manner such that when the pump 29 is reciprocated, fuel from the supply line 34 is drawn into the pump chamber, then forced through the annular channel 52 into one of the engine cylinders through an open distributor valve as will hereinafter be described.

A head 55, mounted upon the shaft 23, is provided with a cam element 56 arranged to engage with and operate the distributor valves 42, 43, 44, 45, 46 and 47 above described, which are disposed equidistantly from the axis of rotation of the shaft 23 essentially as shown. It will be understood that as the head 55 is rotated by the shaft 23, each of the distributor valves is operated successively, thereby connecting the pump chamber 28 with each of the engine cylinders in succession through the annular channel 52 which communicates with the pump chamber.

A plurality of cam elements generally designated 60, 61, 62, 63, 64, and 65, shown in operating position in Figures 1, 2, 3, and 5, and in detail in Figures 6 and 7, are also provided upon the head 55 for operating the injector pump 29 and the sliding valve 35 as will be subsequently described. Referring to Figures 6 and 7, it will be observed that the cam element 64 which is identical with each other cam, comprises a frame

support 64a within which a swinging dog 64b is pivotally mounted, with a flat striking cam surface on its exposed face 64c and with an ear 64d extending through an opening 64e in the head 55 substantially as shown. The cams are 5 arranged in circumferentially spaced relationship upon the head 55 in a circle having its centerpoint coincident with the axis of rotation of the shaft whereby, as the head is rotated, the cams successively operate the pump 29 by 10 striking the end of the pump plunger and pressing the plunger, against the action of the helical spring 30, into the chamber 28. In each instance, at a small time interval before the plunger 15 is thus moved by the cam, a frame of the cam diametrically opposite upon the head engages with and moves the sliding dog 40 against the tension of spring 40a, thus moving the sliding valve 35 from its normal opened position into closed position thereby obstructing the passage 33 and preventing the fuel discharged from the pump chamber from returning to the fuel supply line 34. It of course will be understood that the relative positions of the cams, 60, 61, 62, 63, 20 64, and 65, together with the distributor valve operating cam 56 is such that as the head 55 is rotated the following operations successively occur in this sequence: the cam operating the sliding dog 40 disengages from the same, permitting the spring 37 to move the valve 35 into 25 opened position; the cam pressing the pump plunger 29 into the chamber 28 disengages from the end of the plunger and the spring 30 then moves the plunger in an outward direction, thereby causing fuel oil to be drawn from the supply line 34 through the opened valve 35 and passage 33 into the pump chamber 28; the cam 30 56 engages with one of the distributor valves 42, 43, 44, 45, 46, and 47, moving same into opened position; the frame of one of the cam elements 60, 61, 62, 63, 64, and 65, engages with the sliding dog 40 thereby moving the sliding valve 35 into closed position; one of the cam elements 60, 61, 62, 63, 64, and 65, engages with the projecting end portion of the pump plunger 29 thereby 35 moving same into the chamber 28 and forcing the oil therein into the annular channel 52 from which it passes through the opened distributor valve to the selected cylinder; the cam 56 disengages from the distributor valve, permitting same to move into closed position by action of the spring associated therewith; and the cycle of operations described begins again with the distributor valve next in succession.

It will be obvious that the quantity of fuel injected into the engine cylinders can be altered by adjustment of the stroke of the pump plunger 29. In accordance with the present invention, this is achieved by means of a rotatable circular endless-wedge cam 70, rigidly mounted upon a shaft 71 which is journaled in supporting standards 72 and 73 substantially as shown. A spring 74, connected to the shaft 71 and the support 73, tends to move the cam whereby its thinnest portion is normally disposed within the peripheral channel 55a of the head 55 for purposes hereinafter described. The cam 70, as will be evident in Figures 1 and 3, engages with the projecting ears of the cams 60, 61, 62, 63, 64, and 65 as each is moved into position to operate the injector pump, and by rocking the cams upon their pivots to a degree dependent upon the portion of the cam 70 engaging therewith, the amount of movement of the pump plunger and

hence the volume of fuel injected, can be accurately controlled during operation of the engine. The spring 74 normally holds the cam 70 in a position such that the plunger 29 is inoperative; it is shifted from this position only by the governor as will be described. Rotation of the cam 70 is controlled through a coupling member 75, connected to the engine governor and to an arm 76 mounted on the shaft 71 essentially as shown.

It is desirable, when starting a Diesel-type engine or when operating the engine at low speeds (minimum fuel injection) to retard the injection time. In accordance with the present invention, this is accomplished by rotating the head 55 upon the shaft 23 which is driven from the engine crankshaft thus retarding or advancing the timing of each of the operations in the sequence above described. To achieve this, a lever arm 80 is provided upon the arm 76, which moves when the pump displacement and fuel injection are altered by rotation of the cam 70. A sliding yoke 81 having a wedge surface 82 thereon, that is, this surface is thicker at its upper right-hand side 82a (as seen in Fig. 4) than in its lower left-hand side 82b (as will be seen in Fig. 3). This yoke is coupled with the arm 80 whereby, as the arm moves, the wedge surface also is shifted. A pair of wedge elements 82c and 82d, slidably mounted in keyways in the shaft 23 and each is provided with a flange 82e to abut against the wedge surface 82 of the yoke 81 in a manner such that upon movement of the yoke the wedge elements are shifted in position along the axis of the shaft 23. These members in turn have surfaces 83 and 84 inclined to the axis which engage mating inclined surfaces on the inside of the head 55 so that this shifting of the wedge elements 82c and 82d along the axis will rotate the head 55 relative to the shaft. A spring 85 presses against the flange 82e and the head 55, whereby the head is maintained in position for minimum injection timing. It is thus possible to alter the period of injection simultaneously with alteration of the volume of fuel injected, and both while the engine is in operation.

In Figure 9 a modified form of guide for the pump plunger head is illustrated. The pump or plunger stem 86 is slidably mounted in a block 87 and is pressed outwardly by a spring 88 which engages with a part of the block and with a projecting annular member 89 formed upon the stem. A head 90, formed of hard, wear-resistant material, is freely slidably received in an opening formed in the guide 85 and rests against the end of the stem substantially as shown. This construction is of advantage as the only part subjected to wear, the head 90, can be easily replaced when necessary without requiring replacement of the valve or the plunger, and also prevents distortion of plunger 86 due to striking of cam.

A similar modification of distributor valve mechanism is illustrated in Figure 10 wherein the stem 96 is provided with a cap 97 formed of suitable wear-resistant material and attached to the stem by a pin 98a. The cap also serves to engage with the spring 98 whereby the stem is urged outwardly. A suitable casing 99 surrounds the spring thus protecting same from grit and dirt that would interfere with proper operation, and prevents distortion of the plunger head as above mentioned.

Having thus described the present invention, what it is desired to secure by Letters Patent is:

1. An internal combustion engine fuel distributor injection pump that comprises a block, a rotatable shaft; a plurality of fuel distributor valves therein concentric with said shaft; a head mounted on said shaft near said block; a first cam element upon said head, constructed and arranged for engaging with and operating successively each of said distributor valves upon rotation of the head; a variable displacement plunger-type injector pump also in said block eccentric to said shaft and adapted to be connected to a fuel supply and connected to each of said distributor valves; a series of second cam elements upon said head, constructed and arranged each successively to operate the injector pump upon rotation of the head; means for modifying the action of said second cam elements to vary the displacement of the injector pump; a valve in said block for controlling connection of the pump to the fuel supply; and a third cam element upon said head for engaging with and closing said valve when the pump is discharging fuel through the distributor valves.

2. An injector pump for internal combustion engines as described in claim 1 wherein the means for altering the displacement of the pump comprises a circular member having a helical cam surface pivoted to said block, said second cam elements being rotatable in the direction of movement of said shaft and being constructed and arranged to engage said helical cam surface and said pump whereby the displacement of said pump is altered by the adjustment of said circular member about its pivot.

3. A pump for feeding fuel to a Diesel engine adapted to be connected to receive oil from a fuel supply and deliver it to the cylinders of said engine—said pump comprising a cylinder and piston, a plurality of slide valves concentric about an axis and each slidable parallel to the said axis and each adapted to control the flow of fuel from said pump cylinder to one of said engine cylinders, a rotary member carrying a plurality of cams for operating said pump piston and a cam for operating said slide valves, and stationary means for regulating the total movement of said pump piston to vary the feed of fuel.

4. An internal combustion engine fuel distributor-injector pump that comprises a rotatable shaft, a block, a plurality of fuel distributor valves therein, concentric about said shaft, a head mounted on said shaft near said block, a first cam element upon said head, constructed and arranged for engaging with and operating successively each of said distributor valves upon rotation of the head, a variable displacement plunger-type injector pump also in said block eccentric to said shaft, adapted to be connected to a fuel supply and connected to each of said distributor valves, a series of second cam elements upon said head, constructed and arranged each successively to operate the injector pump upon rotation of the head, a regulating member adjustably fixed on said block, said second cam elements being movable in the direction of movement of said pump and being constructed and arranged simultaneously to engage said regulating member and said pump, whereby the displacement of said pump is altered by the adjustment of said regulating member, a valve in said block for controlling the connection of the pump to the fuel supply.

5. A pump adapted to be connected to receive

fuel from fuel supply and deliver to the cylinders of a Diesel engine, said pump comprising a cylinder and piston eccentric to an axis, a plurality of distributing valves concentrically arranged around about said axis for controlling the delivery of fuel from said pump to the cylinders of the engine in predetermined sequence, a member rotatable about said axis constructed and arranged to be driven in timed relation with the crankshaft of the engine, carrying a plurality of concentrically arranged cams positioned to operate said piston once for each cylinder, said rotatable member carrying also a single cam, in position to operate said distributing valves in sequence and adjustable means mounted in registry with said piston for varying the displacement of said piston.

6. A device in accordance with claim 5, having each of the pump operating cams pivoted to said rotary member and provided with an arm and a stationary but adjustable cam for engaging said arm to vary the displacement of said pump.

7. A device in accordance with claim 5, having each of the pump operating cams pivoted to said rotary member and provided with an arm and a stationary but adjustable cam for engaging said arm to vary the throw of said pump said cam and said arm being so constructed and arranged that the adjustment of said cam will vary the displacement of said pump without making any corresponding variation in the time of discharge of said pump.

8. A pump for feeding fuel to a Diesel engine adapted to be connected to receive oil from a fuel supply and deliver it to the cylinders of said engine, said pump comprising a cylinder and piston, a plurality of slide valves concentric about an axis and each slidable parallel to the said axis and each adapted to control the flow of fuel from said pump cylinder to the point where it is to be admitted to one of said engine cylinders, a rotary member carrying a plurality of cams for operating said pump piston and a cam for operating said slide valves, each of said plurality of cams including a member movable in the direction of movement of said pump piston and stationary but adjustable means for engaging said movable member to vary the extent to which said movable member moves said piston during the rotation of said movable member and said movable member having a trailing edge constructed and arranged to maintain the exact timing of the close of the piston movement regardless of the adjustment of the piston displacement.

9. A pump for feeding fuel to an internal combustion engine, a block having a piston pump therein, a member rotatably mounted adjacent to said block, having an operating element thereon provided with a pump engaging surface, a cam adjustably fixed on said block for engaging said operating element as the latter engages the piston of said pump to adjust the displacement of said piston, said surface of said operating element being so constructed and arranged with regard to its pivot that the timing of the moving of the piston is not altered by changing the movement of the operating element to alter the displacement of the piston.

10. A device of the character described comprising a block having a piston pump and a piston valve disposed therein about parallel axes, a member mounted for rotation relative to said block about an axis eccentric to both the said axes, a cam upon said member for operating said

valve, and a second cam thereon for operating said pump, a means mounted on said block for varying the action of said last mentioned cam on said pump to vary the displacement thereof.

11. A device of the character described comprising a block having a piston pump and a piston valve disposed therein about parallel axes, a member mounted for rotation relative to said block about an axis eccentric to both the said

axes, a cam upon said member for operating said valve, and an element movably mounted on said member to engage said pump as said member rotates and a circular cam element mounted on said block in position to be engaged by said movable element simultaneously with said pump, and constructed and arranged to vary the movement of said piston without varying the time thereof.

EUGENE SILBER.
